United States Patent Office

Des. 197,099
Patented Dec. 10, 1963

197,099

BOAT

John L. Torreson, New York, N.Y., and Robert J. Scott,
Colts Neck, N.J., assignors to Hydro-Marine, Inc.,
Kirkland, Wash., a corporation of Washington

Filed Sept. 17, 1962, Ser. No. 71,724

Term of patent 14 years

(Cl. D71—1)

Fig. 1.

Fig. 2.

Des. 197,099

PAGE 2

FIG. 1 is a bow view of a boat showing our new design;
FIG. 2 is a stern view thereof;

FIG. 3 is a view in side elevation thereof; and

FIG. 4 is a bottom plan view thereof.

The dominant features of our new design are shown in full lines.

We claim:

The ornamental design for a boat, substantially as shown and described.
